United States Patent Office.

W. W. BURSON, OF ROCKFORD; ILLINOIS.

Letters Patent No. 83,923, dated November 10, 1868; antedated October 31, 1868.

IMPROVEMENT IN AUTOMATIC GATE.

The Schedule referred to in these Letters Patent and making part of the same.

To all whom it may concern:

Be it known that I, W. W. BURSON, of the city of Rockford, in the county of Winnebago, and State of Illinois, have invented a new and useful Approach-Opening or Automatic Gate; and I do hereby declare that the following is a full, clear, and exact description of the construction and operation of the same, reference being had to the annexed drawings, forming part of this specification, in which—

Figure 1 shows a side elevation of the gate, the full lines showing the several parts in the position when closed, and the dotted lines the same when open.

Figure 2 is an end elevation of the same.

Figure 3 is a plan view of the levers F F'

Figure 4 is a cross-section of the fig. 3, on the line 2-2.

My invention consists in constructing a gate in such manner as to be easily opened and closed by a person in a wagon or carriage, or on horseback, without dismounting, and consists of certain combinations of devices hereinafter to be set forth.

In the drawing, A is the base, representing the ground or frame to receive the posts E E', and the posts B C C', which support the gate P by the elevated ways D D', the friction being relieved by the sheaves a a'. The right-angled swinging arm K, pivoted to post B at c, attaches the pitman L, which is hinged to the gate-bar r at d, (fig. 1.) The levers F F', hinged to the cross-beam N at f f', operate the right-angled swinging arm K, by means of the connecting-pieces I I' taking hold of the arm K at g.

For convenience of operation, the pendants H H' are attached to the outer end of levers F F', and communicate the same motion to them as if taken hold of directly. The cross-way D is hinged at h to the post B, and the other end can be raised, as shown in the dotted lines, (fig. 1.)

The gate P is constructed by fastening the bars r r- r between the pieces O O and O' O', with diagonal bracing, if desired. The pieces O O are of sufficient length to reach the elevated way D, receiving the friction-sheave a between them, which supports the front end of the gate. The pieces O' O' secure between them the bars at the rear end of the gate, and also the sheave a', and are about the height of the gate.

The wire, m, connects the pendants H H', and enables the gate to be opened from the opposite side from which it has been fastened closed, as described further on.

In operation, the gate P being closed, as shown in fig. 1, full lines, the pendant H or H' is drawn downward, which swings lever F, hinged at f, drawing upward the right-angled projection of swinging arm K, acting through connecting-pieces I I', which movement pushes open the gate P by pitman L. Pushing upward on the pendant H reverses the above-mentioned movements, and closes the gate. If it is desired to fasten the gate securely closed, the pendant H or H' is placed

on top of the post E E', in which situation it cannot be opened until the pendant is removed from the post, as above described. If it is desired to open the gate from the opposite side from which it was fastened, the pendant is readily drawn from the top of the post by drawing upon the wire, m.

My aim has been, in this invention, to furnish an approach-opening or automatic gate, which should combine cheapness, simplicity of construction, and durability, and at the same time be so arranged as to be made with a "farmer's kit of tools," without calling into requisition either the blacksmith or machinist. Accordingly, it will be seen that the gate can readily be constructed entirely of wood, although iron bolts, when obtainable, are of course preferable to wooden pins, as also the friction-sheaves are better made of iron than wood.

In this invention, especial attention is invited to the following explanation of the devices employed to accomplish the foregoing-mentioned results.

First, the gate is constructed by fastening the bars r r- r between the perpendicular pieces O O and O' O', which serve the double purpose of holding the bars in place, and also the friction-sheaves a a', which support the gate on the ways D and D', and since these supports pass on both sides of the ways, the gate cannot be thrown off the track, as is the case when the sheave is supported on one side only, as is usually done. This plan of supporting the friction-sheaves a a' between two wooden supports is much cheaper than the usual iron fastening given the sheave when supported only from one side.

Second, the way D is placed over the carriage-drive, at the desired height, and the way D' is placed lower, so that it may pass between the gate-bars. The advantages of this arrangement of the ways, over the usual plan of having them at the same height, are that the gate will be very much less affected by winds in opening and closing, while it saves the extra height of the post C' and hangers O' O'.

Third, it will be observed that the weight of the swinging arm K would tend to start the gate open when closed, and closed when open, but as it hangs perpendicularly at the half-way distance, it requires power to move it in either direction. To overcome this tendency of arm K, one or both of the ways D D' are curved upward from both ends, so as to make the movement of the gate about of equal force.

Fourth, the way D is pivoted at h to the post B, the other end resting on a pin in post C, and is held in position by a notch in the under side of the way-piece. The advantages of this arrangement over a solid fastening of the way-piece to the posts are, that it need not be placed higher over the carriage-drive than to permit the usual vehicles to pass under it readily, and when any higher object, as a load of hay or straw, has to pass under it, the driver on the load can easily raise the way-piece, so that the load goes under it. It also

saves the extra height of posts B and C, and hanger-pieces O O, and still more important is the more positive guiding of the gate in time of hard winds. If the way D were jointed and hinged outside of the resting-place of sheave *a*, when the gate was open, it could then be raised perpendicularly, offering no hindrance to the passage of the tallest object through.

Fifth, the levers F F' are hinged to the cross-beam N, which is fastened to post B. These levers are hinged at *f* to the connecting-pieces I I', which take hold of the right-angled part of swinging arm K. The lower end of arm K is hinged to the balanced pitman L, which is hinged to the gate P at *d*. The pendants H H' are fastened to the outer ends of levers F F'. It will be seen that drawing down the pendant H will, through the medium of lever F, connecting-piece I, swinging arm K, and balanced pitman L, open the gate P, and pushing upward on the pendant will reverse all these movements, and close it. This arrangement and combination saves the usual ropes, chains, friction-sheaves, and distance-posts to support the same, and is free from the objection of being affected by rain and sleet, as is the case with ropes and chains, besides being much cheaper, and more durable.

Sixth, the levers F F' are hung obliquely upon the piece N, so that the pendant H shall be in reach of the driver, as also obliquely to the perpendicular plane, as it would not be convenient to draw directly downward upon the lever F from the carriage. To accommodate these two conditions, the levers are placed at the desired angles to each plane.

Seventh, the levers F F' are constructed of three pieces, *i*, running the length of the lever, placed on its edge, *i*', reinforcing this piece past the pivot-pin *f*, and *i*, placed over these, stiffening the lever sidewise, (fig. 4.) This construction of the levers renders them stiff and light, giving them extra strength where the greatest strain comes, and also partly balances them.

Eighth, the pendants H H' are fastened to the outer ends of levers F F', in such manner that they can swing freely, either lengthwise or crosswise of the lever, which movements are necessary to accommodate the convenience of drawing and pushing them, and frees the pendants from the danger of being broken off by being run against by anything. This fastening is made by cutting a curved recess in lever F, near its outer end, on the under side, and making a curved opening or fork in pendant H, then making a hole in pendant H, about on a line with the under surface of the lever, through which hole a wire or cord is passed, and over the lever, connecting the two with a fastening admitting of the movements before spoken of. Other methods

of making this jointed connection may, of course, be used, but this plan is chosen on account of its adaptability to the wants of the farmer.

Ninth, it will be seen that the pieces I I', connecting levers F F' with swinging arm K, cannot be fastened rigidly to either piece, but each end must roll somewhat upon its fastening. To accommodate these movements, and at the same time furnish the cheapest possible fastening, the parts referred to are somewhat rounded, and the holes in pieces I I' are elongated or enlarged, for the play of the bolts, permitting the motions required.

Tenth, the pitman L, forming connection between swinging arm K and the gate P, is extended beyond its pivot, *d*, and the extension enlarged or weighted, to assist in balancing the parts, and equalizing the movements of the gate. Without this balancing of pitman L, and the curve of way D, as hereinbefore described, the weight of the swinging lever K and pitman L would tend to open the gate partly when closed, and close it partly when open, but the pitman can be so balanced as to overcome this tendency, and to assist in closing and opening fully the gate.

Eleventh, the pendants H are connected by the wire, *m*. When it is desired to fasten the gate closed, the end of the pendant is placed on top of the post under it, which holds it securely closed until it is removed from the post, which may be done from the opposite side from which it was fastened, by means of the wire, *m*.

From the foregoing description of the devices herein used to accomplish the desired result, it will be seen that simplicity of construction, and durability of the parts, have been leading objects throughout; and I shall desire to secure the benefit of this plan of construction, as equally effective with complicated devices, and much more valuable for general use.

What I claim as my invention, and desire to secure by Letters Patent, is—

1. The combination and arrangement of levers F F', pendants H H', connecting-pieces I I', arm K, and ways D D', when the whole are constructed and operated substantially as and for the purpose set forth.

2. Constructing the way D or D' with suitable curve to overcome the gravity of swinging arm K, substantially as specified.

3. The combination and arrangement of the pendants H H', wire, *m*, and posts E E', operating substantially as and for the purpose set forth.

W. W. BURSON.
